UNITED STATES PATENT OFFICE.

WINFRED A. STUBBLEBINE, OF ALLENTOWN, PENNSYLVANIA.

RECUPERATOR-FURNACE.

1,111,414.

Specification of Letters Patent. Patented Sept. 22, 1914.

Application filed October 31, 1913. Serial No. 798,523.

To all whom it may concern:

Be it known that I, WINFRED A. STUBBLEBINE, a citizen of the United States, residing at Allentown, in the county of Lehigh and State of Pennsylvania, have invented certain new and useful Improvements in Recuperator-Furnaces; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in recuperator furnaces and the object in view is to produce a simple and efficient apparatus of this nature so constructed as to provide for an increased production in material being treated over the ordinary types of furnaces now in use.

The present invention comprises an apparatus of this nature having various details of construction and combinations and arrangements of parts which will be herein-after fully described, shown in the accompanying drawings and then specifically defined in the appended claim.

I illustrate my invention in the accompanying drawings, in which:—

Figure 1 is a vertical central sectional view longitudinally through the furnace. Fig. 2 is a section on line 2—2 of Fig. 1. Fig. 3 is a sectional view on line 3—3 of Fig. 2, and Fig. 4 is a sectional view on line 4—4 of Fig. 1.

Reference now being had to the details of the drawing by letter, A designates the fire box of the furnace having a grate D therein and A' is an opening formed above the bridge wall F and leading into the working chamber B which is the portion of the apparatus into which the charge of iron or steel to be melted or preheated is placed and in which it is necessary to maintain an intense heat. Said furnace is provided with a fuel opening C through which the coal is allowed to be inserted upon the grate D. A pipe, designated by letter E, communicates with a space below the grate and through which a blast of air may be introduced into the furnace. Other pipes, designated by letter G, having branching portions communicate with the lower portion of the chamber G' in which the checkered

arrangement of fire brick G² is located with spaces intermediate the blocks and through which the blast of air coming from the pipes G is allowed to pass and become heated before emerging into the space in the upper end of the compartment G' from which the preheated air makes exit into the passageways J formed in the opposite side walls of the furnace, said passageways having ducts K leading therefrom diagonally into the working chamber B. A pipe H communicates, through the branching pipe H', with the upper portion of the chamber G' and its ends open into the flues J, as shown clearly in Fig. 2 of the drawings. The front wall of the furnace adjacent the chamber from which the pipes H lead is provided with series of flues L affording a means of communication between the fire chamber A and the compartment M which in turn communicates about the circumferences of the pipes P and H with the passageways J. The chamber B' has an end wall N' in contact with the wall N and a horizontal partition N² separating the chambers G' and M.

The operation of my furnace will be readily understood and is as follows:—The combustion of the fuel within the fire chamber will be expedited by the blast of air introduced through the pipes E and the greater part of the gas in the fire chamber will pass over the bridge wall F into the working chamber B. A separate blast will be supplied to the chamber G' through the pipes G and which passes through the spaces intermediate the brick G² where it becomes preheated before entering the pipes H, H and into the passageways J. The blast passing from the pipes H, H into said passageways will create a suction which will draw a certain percentage of the gas from the fire chamber through the ports L in the wall of the fire chamber and which will heat the air in the chamber M about the pipes H, thus further preheating the air which passes through the pipes H and before it makes exit into the passageways J. As the gases emerge from the pipes H and commingle with the gases coming from the chamber M, they will be mixed and make exit through the ducts K into the working chamber. After the furnace is in operation, the brick work becomes thoroughly heated and the wall N, being next to the intense heat of the fire chamber, becomes red hot through and

through and this heat is still further taken up by the checkers G². The air from the pipes G, before entering the pipes P, is pre-heated by coming in contact with the checker-work.

The admission of this mixture of pre-heated air and gas through the ducts K will produce a very high degree of heat in the working chamber, thus enabling the operator to obtain a much increased production over that which would be possible to obtain by the ordinary types of furnace.

What I claim to be new is:—

A recuperator furnace having communicating fire and working chambers, a grate with a blast pipe communicating with a chamber below the grate, a compartment adjoining the fire chamber, a checker work within said compartment with a chamber above and below the checker work and communicating with each other through the

latter, air supply pipes leading into the chamber below the checker work, a preheating chamber above said compartment, a passageway leading from the preheating chamber with flues leading from said passageways into the working chamber, a pipe communicating with the chamber above the checker work and extending into said preheating chamber and provided with branching pipes extending into and opening into said passageway, the front wall of the furnace intermediate the fire and preheating chambers and above said compartment having flues therein, as set forth.

In testimony whereof I hereunto affix my signature in presence of two witnesses.

WINFRED A. STUBBLEBINE.
